UNITED STATES PATENT OFFICE.

FRANK P. PFLEGHAR, OF NEW HAVEN, CONNECTICUT, ASSIGNOR TO F. P. PFLEGHAR & SON,
OF NEW HAVEN, CONNECTICUT, A FIRM.

BUTTON.

No. 867,924.

Specification of Letters Patent.

Patented Oct. 8, 1907.

Application filed October 27, 1905. Serial No. 284,607.

To all whom it may concern:

Be it known that I, FRANK P. PFLEGHAR, a citizen of the United States, and a resident of New Haven, in the county of New Haven and State of Connecticut, have invented a new and useful Improvement in Buttons, of which the following is a specification.

My invention relates to a button and more particularly to a button for holding a vehicle curtain securely fastened.

10 In vehicles provided with curtains exposed to great air pressure, for instance, curtains on high speed automobiles, great difficulty is experienced in holding the curtains securely fastened when lowered for use, and, at the same time, providing for quickly and easily 15 unfastening the curtain when it is desired to raise it out of use.

My present invention is directed to means for overcoming this difficulty and consists in a button comprising a stationary hollow stud over which an eye in 20 the curtain is passed, a bolt seated and movable transversely in the said stud and a rotary key and eccentric extending into the stud and engaged with the bolt for projecting the bolt laterally from the stud and withdrawing it.

25 In the accompanying drawings, Figure 1 is a front view of a portion of a curtain with the button in locked position, Fig. 2 is a top plan view, Fig. 3 is an enlarged horizontal section in the plane of the line A—A of Fig. 1, Fig. 4 is an enlarged vertical section in the 30 plane of the line B—B of Fig. 1, Fig. 5 is a similar view showing the button in unlocked position, Fig. 6 is a back view of the stud showing the retaining spring in position, Fig. 7 is a similar view with the retaining spring removed and showing the base of the eccentric 35 in operative position; Fig. 8 is a rear end view of the key, Fig. 9 is a front end view of the eccentric, Fig. 10 is a rear view of the locking dog or bolt in detail. Fig. 11 is a side view of the key in detail, and Fig. 12 is a side view of the rotary disk.

40 The curtain is here represented by 1 and may be of any material such as is commonly used for the purpose. It is provided with an eye 2 surrounded by a metal gromet 3 for protecting its wall as is common.

The stationary stud which supports the movable 45 parts of the button consists of a base plate 4 from which a hollow neck or barrel 5 extends outwardly for receiving the eye of the curtain. Transversely through the neck 5 there extends an opening 6 in which the locking bolt or dog 7 is seated and in which the said 50 bolt or dog has a sliding movement. The bolt or dog 7 has its locking end partially cut away on the inner or rear side to afford an extended flat bearing 8 on the gromet and at the same time to provide for the thickness of the curtain without unduly lengthening 55 the neck of the stud, and the said bolt has its ends

rounded to conform to the curved surface of the neck 5 of the stud in which it is mounted. The bolt or dog is further provided with a transverse slot 9 open to the rear and with a transverse slot 10 open to the front and merging into the slot 9.

60

The hollow neck 5 of the stud has mounted therein a rotary disk 11 having a flanged base 12 and an eccentric projection 13 extending into the transverse slot 9 in the bolt when the latter is in position in the stud.

65 The flanged base 12 is provided on its rear face with indentations 14, 15, for the reception of a nose 16 of the retaining spring 17 to hold the eccentric in its positions with the bolt 7 advanced and withdrawn.

The retaining spring 17 is located in a shallow recess 18 in the rear face of the base 4 of the stud, the 70 said recess being conveniently undercut at one end to retain the spring and a small screw 19 may be employed.

75 The eccentric projection 13 is operated by means of a key 20 provided with a central pin 21 which extends rearwardly through the disk which carries the eccentric 13 and has its rear end provided with a nut 21* to hold the key in position. The key 20 is further provided with a pin 22 eccentrically set therein and extending rearwardly into the eccentric projection 13. The key 80 20 is further preferably centered in the outer end of the neck 5 of the stud by means of a short cylindrical projection 23 on its inner or rear end which fits in a shallow recess 24 in the outer end of the neck. The maximum diameter of the key 20 is intended to be not materially 85 greater than the maximum diameter of the neck 5 of the stud as the eye of the curtain is passed over the key as well as over the stud in securing and releasing the curtain.

90 In assembling the parts, the bolt 7 is first placed in position in the opening 6 in the neck 5 of the stud with the flat bearing 8 facing inwardly, the rotary disk 11 then inserted through the base of the stud with its eccentric projection 13 in the recesses 9 and 10 in the bolt and the key then placed in position from the front 95 of the stud and its central pin made fast to the disk 11 by the nut 21*. The retaining spring 17 is then placed in position in the shallow recess 18 in the base 4 of the stud and the button as a whole may be secured to a suitable support for example, the support 25, by means 100 of screws 26, 27, extending through the base 4 and through the opposite ends of the spring 17 into the support.

105 In operation, the slot 10 in the bolt permits the eccentric projection 13 to be turned in one direction only by the pin 22, the latter resting against the bottom wall of said slot when the key is turned to its limit in either of two opposite directions. The nose 16 of the retaining spring 17 will engage the indentation 14 when the eccentric projection 13 is at one limit of its rotary move- 110

ment, for instance, to advance the bolt, and the other indentation 15 when the eccentric is at the opposite limit of its rotary movement, for example, to withdraw the bolt. When the eye of the curtain has been passed 5 over the stud and the bolt advanced, no strain on the curtain can exert a pressure on the bolt in a direction to release it, as any outward pressure is at right angles to the direction in which the bolt moves.

This structure also provides for placing the button 10 complete on the support to which the curtain is to be fastened, leaving the curtain itself free from any part or member of the button and provided simply with an eye.

The structure is neat in appearance, strong and durable and may be manipulated easily and quickly.

15 What I claim is:—

1. A button comprising a stationary hollow stud for receiving an eye in the curtain, a bolt seated in and movable transversely of the stud and a rotary key and eccentric for operating the bolt.

20 2. A button comprising a hollow stationary stud for receiving an eye in the curtain, a bolt seated in and movable transversely of the stud, an eccentric mounted in the stud and adapted to be engaged with the bolt for operating it and a key mounted on the outer end of the stud and engaged with the eccentric for operating it.

25 3. A button comprising a hollow stationary stud for

receiving an eye in the curtain, a bolt seated in and movable transversely of the stud, an eccentric engaged with the bolt and removable only from the rear face or end of the stud and a key engaged with the eccentric and removable only from the outer end of the stud. 30

4. A button comprising a hollow stationary stud provided with a shallow recess in its base, a bolt movable transversely of the stud, a disk provided with an eccentric projecting therefrom for operating the bolt and a retaining spring engaged with the said disk for retaining it and hence the bolt in the desired position. 35

5. A button comprising a hollow stud, a bolt seated transversely in the stud and provided with communicating slots extending transversely through it, an eccentric 40 located in one of the slots and a key having a projection extending through the other slot into engagement with the eccentric.

6. A button comprising a hollow stud, a bolt seated transversely therein and having its locking end partially 45 cut away, an eccentric for projecting the bolt from the stud and withdrawing it, and a key for operating the eccentric.

In testimony, that I claim the foregoing as my invention, I have signed my name in presence of two witnesses, 50 this 20th day of October 1905.

FRANK P. PFLEGAR.
